UNITED STATES PATENT OFFICE

165,803

BRASSIÈRE SLIP

Jess Train, New York, N. Y., assignor to Tranel,
Inc., New York, N. Y., a corporation of New York

Application September 12, 1951, Serial No. 16,610

Term of patent 3½ years

(Cl. D3—26)

To all whom it may concern:

Be it known that I, Jess Train, a citizen of the United States of America, residing in the city of New York, county of Queens, and State of New York, have invented a new, original, and ornamental Design for a Brassière Slip, of which the following is a specification, reference being had to the accompanying drawing, forming part thereto.

I claim:

The ornamental design for a brassière slip, substantially as shown.

JESS TRAIN.
